DESIGN FOR A PASTE MOLD GLASS MACHINE

Frederick William Stewart, Weston, and Matthew James Kelly, Elkins, W. Va., and Ashley J. Reek, Carrick, Pa., assignors to Kelly Foundry and Machine Company, Elkins, W. Va., a corporation of West Virginia

Application August 27, 1940, Serial No. 94,638

Term of patent 14 years

To all whom it may concern:

Be it known that we, Frederick William Stewart, Matthew James Kelly, and Ashley J. Reek, citizens of the United States of America and residents, respectively, of Weston, county of Lewis, and State of West Virginia, Elkins, county of Randolph, and State of West Virginia, and Carrick, county of Allegheny, and State of Pennsylvania, have invented a new, original, and ornamental Design for Paste Mold Glass Machine, of which the following is a specification, reference being had to the accompanying drawings, forming part thereof.

Figure 1 is an elevation of a paste mold glass machine, showing our new design.

Figure 2 is a top plan view of the said machine, the base of the machine being omitted.

Figure 3 is a sectional plan view taken on the line 3—3, Fig. 1 showing the base of the machine.

Figure 4 is an end elevation of Fig. 3.

Figure 5 is a section taken on the line 5—5, Fig. 1.

We claim:

The ornamental design for a paste mold glass machine, substantially as shown.

FREDERICK WILLIAM STEWART.
MATTHEW JAMES KELLY.
ASHLEY J. REEK.
